UNITED STATES PATENT OFFICE

HEINRICH BANGERT AND MATHIEU PETERS, OF DUSSELDORF, GERMANY, ASSIGNORS
TO OFENBAU-GESELLSCHAFT MIT BESCHRANKTER HAFTUNG, OF DUSSELDORF,
GERMANY

APPARATUS FOR MOVING INGOTS OR MASSES IN FURNACES

Application filed March 23, 1926, Serial No. 96,730, and in Germany May 23, 1925.

In order that ingots or slabs to be heated in furnaces may be uniformly heated, it is necessary to turn or to move them from time to time. Hitherto this has been done by hand in a cumbersome way or by apparatus built into the furnace. It will be understood, however, that these apparatuses are subjected to great wear, so that in practice it is preferred to turn or move the blocks by hand.

According to the invention a carriage is provided to run upon rails laid parallel to and in front of the furnace, the carriage being provided with a mechanically driven rod which is movable transversely to the furnace. The rails may be placed on the floor in front of the furnace, or they may be applied upon a suspended track. In the use of this apparatus, the rod is inserted into the furnace and pushed between two ingots. By moving the carriage along the rails, the ingots may be tilted and rolled. The movable rod may also be provided to oscillate in the horizontal plane upon the carriage in order that the ingots may be moved on the movement of the rod when the carriage is stationary. By means of such an apparatus several blocks can be moved together as desired, or they can be arranged singly and spaced out upon the track, but the track does not require to be inclined but may be disposed in the horizontal plane.

According to the invention, moreover, the apparatus is constructed in such manner that it can be used for turning angular ingots and this is effected by shaping the forward end of the rod that is inserted into the furnace, in such manner that it engages the ingots underneath and also holds them at the sides, whereby the rod which may be inserted into the furnace and withdrawn therefrom has imparted to them both an axial and a radial movement.

For this purpose the rod is advantageously provided circular in cross-section and is provided with teeth or ribs all round its periphery, so that the engagement of the pinion which operates the rod is maintained as the rod is turned. To rotate the rod it is advantageously provided with a toothed or

worm wheel, which carries the rod with it during working by means of a wedge mounted in a longitudinal groove in the rod and turns the ingot held by it as is desired.

The drawings illustrate two constructions 55 of apparatus according to the invention by way of example;

Figure 1 is a plan of the apparatus according to the invention.

Figure 2 is an elevation corresponding to 60 Figure 1, and

Figure 3 is an illustration of a part of the apparatus.

Figures 4, 5 and 6 are corresponding views of a constructional modification. 65

As illustrated in Figures 1 to 3, the travelling frame 1 runs upon the rails 2 of the heating or welding furnace 3, and it is provided with a toothed rod 4 which is circular in cross-section and which is moved forward 70 and backward by means of the wormgear illustrated in the drawings, and by the pinion 6 and the motor 7. The rod 4, together with the driving motor 7 and the base-part 8 oscillate in the horizontal plane. The base 75 part 8 has mounted upon it a second motor 9, which drives a worm 11 by means of the toothed wheel and pinion 10, 10¹. The worm 11 engages with the worm wheel 12 and is mounted in bearings 13 on both sides 80 of the rod 4. The worm wheel 12 (Figure 3) is slidably mounted on the rod 4 and is merely connected by one or more keys 13¹ with the rod 4. The key 13¹ is inserted in a longitudinal groove 14 in the rod 4, so 85 that the latter, without being affected by the driving gear 9, 10, 11, can be moved forward and backward. It will be understood that the rod 4 can be turned about its longitudinal axis by means of the driving 90 gear 9, 10, 11 without disturbing the engagement of the driving pinion 6. The two driving gears 7, 6 and 9, 10, 11 thus render it possible for the rod 4 to be rotated as well as moved in the axial direction, it being a 95 matter of no importance whether such movements are made simultaneously or separately.

The rod 4, which is supported upon the roller 15 and may be made hollow to enable 100

it to be water-cooled, is provided at its forward end with an angle part 15¹, by means of which the ingots 17 in the furnace 3 are engaged underneath and are turned over by rotation of the rod 4 on the operation of the motor 9. Furthermore, the ingots may be moved about in the furnace so that the best position may be secured for uniformly heating the ingots. The angle part 15¹ 10 may at the same time be provided for working upon the surface of the ingots and by this means the slag and sinter adhering to the falling dust may be removed from the furnace.

15 Figures 1 to 3 illustrate merely one construction of apparatus according to the invention, but the invention is not limited thereto, as it is not confined to the manner and disposition of the driving gear for the 20 rod. It is similarly a matter of subordinate importance whether the rod 4 can move merely axially in addition to its radial movement or whether the rod may be movable in the horizontal plane.

25 As illustrated in Figures 4 to 6, the end of the rod 4 is toothed so that it can be moved by the motor 18 by means of a set of gears. The motor 19 is provided for moving the 30 whole apparatus along the rails. The rod 4 with its driving gear is provided to move in the horizontal plane upon the carriage. In using this apparatus, the rod is inserted into the furnace after the door 20 has been raised, and is pushed between two contiguous substantially cylindrical ingots. The ingots 35 may, however, be moved by swinging the rod 4. Thus, in this manner very quick movements can be made, if desired. A horizontal track may advantageously be used 40 and the separate ingots are disposed by means of the rod in such manner that the adjacent ingots may be spaced out and the flames can play evenly upon them.

45 We claim:

45 1. Apparatus for turning over blocks in a heating furnace, comprising in combination a supporting frame, a rod supported upon the said frame adapted to have an oscillating movement in a substantially horizontal 50 plane, to be rotatable about its longitudinal axis, and to be axially movable, said rod being cylindrical and having teeth and spaces between the teeth to extend around its periphery, and means carried upon the said frame by which the said rod may have imparted to it an oscillating movement in a horizontal plane, a movement of rotation and an axial movement, the means employed 55 for causing the rotation of the rod and its axial movement operating directly upon the rod itself, and the means for imparting axial movement to the rod comprising a pinion adapted always to be in engagement with 60 said teeth on the rod notwithstanding its ro-

65 tation, substantially as hereinbefore described.

2. Apparatus for turning over blocks in a heating furnace, comprising in combination a supporting frame, a carrier rotatably mounted upon the said frame, a rod supported upon the said carrier and adapted to be rotatable about its longitudinal axis and to be axially movable independently of the other elements of the apparatus, prime movers, such as electric motors supported upon the said carrier, and gearing between the respective prime movers and the rod by which the said rod may have imparted to it respectively a movement of rotation and an axial movement independently of the other elements of the apparatus, substantially as hereinbefore described.

3. Apparatus for turning over blocks in a heating furnace, comprising in combination a supporting frame, a rod supported upon the said frame adapted to have an oscillating movement in a substantially horizontal plane, to be rotatable about its longitudinal axis, and to be axially movable, said rod being cylindrical and having teeth and spaces between the teeth to extend around its periphery, means carried upon the said frame by which the said rod may have imparted to it an oscillating movement in a horizontal plane, a gear wheel embracing the said rod and slidably connected thereto, means carried upon the said frame for effecting the rotation of the said gear wheel to give a movement of rotation to the said rod, and means for imparting axial movement to the rod also carried by the said frame and comprising a pinion adapted always to be in engagement with the said teeth on the rod notwithstanding its rotation, substantially as hereinbefore described.
